UNITED STATES PATENT OFFICE.

EDWIN FIDELL, OF JERSEY CITY, NEW JERSEY.

CONVEYING AND DELIVERING MEANS FOR PACKAGING-MACHINES.

SPECIFICATION forming part of Letters Patent No. 766,234, dated August 2, 1904.

Application filed March 4, 1903. Serial No. 146,058. (No model.)

To all whom it may concern:

Be it known that I, EDWIN FIDELL, residing in Jersey City, Hudson county, and State of New Jersey, have invented certain new and 5 useful Improvements in Conveying and Delivering Means for Packaging-Machines, of which the following is a specification.

The subject of the present invention is a novel means for conveying and delivering to 10 packaging-machines measured quantities of dry material in reduced or granular condition, the said means having for its more prominent objects increased capacity as compared with prior arrangements for a similar purpose, 15 positiveness and efficiency of operation, as well as simplicity and durability of construction.

With the above and other purposes in view 20 the novel conveying and delivering means comprises a peculiar arrangement of movable frame carrying a series of invertible boxes conveniently disposed so that a plurality of the same can during the movement of the frame have measured quantities of the mate- 25 rial deposited therein, together with provision whereby the said boxes will be automatically inverted in regular succession as they arrive at the discharge-point.

There are other important features and de- 30 tails connected with the invention, which are explained at length in the subsequent extended description. Among these may be noted the devices for maintaining the boxes in a non-discharging position throughout their travel 35 with the frame, except at the point of their discharge, said devices at the same time presenting no interference with the operations of depositing the material within the boxes during their movement with the frame.

40 The overhanging character of the means permits a horizontally-rotatable box-carrier to be employed for delivering directly to the hopper of the packaging-machine, which latter can be compactly disposed relative to the 45 novel conveying and delivering means by occupying a position beneath the overhang of said means.

In the accompanying drawings, forming part of this specification, Figure 1 is a plan 50 view of a conveying and delivering means

embodying my invention. Fig. 2 is a vertical elevation of the construction disclosed in Fig. 1, the hopper and a portion of a packaging-machine being illustrated in outline. Fig. 3 is a longitudinal sectional view of one of the 55 boxes and certain appurtenances, the parts being illustrated on an enlarged scale. Fig. 3^a is an inner end view of said box and appurtenances. Fig. 4 is an enlarged detail plan view of one of the sector-shaped keepers for 60 normally maintaining the boxes in their non-discharging positions. Fig. 4^a is a central longitudinal view of the keeper shown in Fig. 4. Fig. 5 is a detail view, partly in section, of parts supported by the standard. Fig. 6 is a 65 detail view of the friction-trackway, dotted lines illustrating the position of two of the box-rollers thereon. Fig. 7 is an enlarged detail view illustrating the manner of pivoting the keepers. 70

Similar reference characters are employed to designate corresponding parts throughout the several figures of the drawings where they occur.

I have represented the rotating frame and 75 coacting parts as being supported in an elevated position by a standard A, mounted on a base A', fixedly secured in position, the upper portion of the standard overhanging and provided with a bearing *a*, in which is rigidly 80 clamped the lower end of a vertical spindle B. Also rigidly connected with the bearing are the inner ends of two arms C and D, disposed radially with respect to each other and shown as spaced at about ninety degrees apart. 85

On the outer end portion of the arm C is a horizontal track-segment C', curved concentric with the axis represented by the spindle and of a length proportionately as represented in dotted and full lines, Fig. 1. This section 90 partakes of a limited yielding character, which in the drawings is provided for by a spring-seated bolt *c*, supporting said trackway and adjustably secured by a nut *c'*, engaging its lower threaded portion *c*² beneath the arm C. 95 The spring being expanding permits the nut *c'* to be manipulated to adjust the degree of resistance with which the trackway is adapted to yield.

Rotatably mounted upon the spindle B im- 100

mediately above the arm D is the box-carrying frame comprising a central hub having radially-projecting sockets e , in which are rigidly engaged the inner ends of a corresponding number of radially-disposed rods e' , connected at their outer ends to a ring E.

Revolute with the hub of the box-carrying frame is a horizontal beveled gear-wheel E', and upon the spindle B above and independently of the wheel E' is a bracket F, having a lower horizontal portion f , providing a bearing for the inner end of a horizontal shaft F', adapted to turn therein, the outer portion of said shaft being revolvably supported in a bearing d , carried by the outer portion D' of the arm D, vertically bent at a point considerably external to the periphery of the ring E. Secured on the shaft F' is a bevel gear-pinion F'', meshing with the wheel E'. The shaft F' proximate to the ends of the bearing has suitable means, as collars f'' , for preventing end movement of the shaft and maintaining the pinion in proper driving relation to the gear-wheel. On the outer projecting end of the shaft is a sprocket-wheel f''' , designed to be driven by a pitch-chain f''' from any suitable source of power.

The bracket F has at one side a small boss f^4 , provided with a threaded perforation for a screw f^5 , by which said bracket may be rigidly clamped in position on the stem. Radially projecting from the opposite side of the bracket and in the direction of the point where the box discharge is to take place is a horizontal socket f^6 , in which is rigidly connected the inner end of an outwardly and downwardly curved rod g , supporting on its lower end an extended horizontal shoe G, curved concentric with the stem and having its ends g' turned upward to a slight extent and with a moderate curvature. This shoe G is located in a slightly higher plane than the upper edge of the ring E and at a point considerably within the inclosed area of the same.

A number of boxes H are arranged around the periphery of the ring E and in closely-associated relation, said boxes being radially disposed with respect to said ring and each comprising a receptacle, the sides h , bottom h' , and outer end h'' of which are disclosed as being of sheet metal, while the inner end is presented by an appropriately-shaped part h^3 of a casting H'. This casting integrally includes a tubular sleeve h^4 and roller h^5 , rigidly thereon.

A comparatively elongated bolt I has a disk-like head i seated against the part h^3 of the casting, said bolt bearing loosely in the sleeve h^4 and having its inner end portion bearing and clamped rigidly in the ring E by a nut i' , which engages the inner projecting threaded end of the bolt and clamps the ring against a shoulder i'' of the nut.

By reference to Figs. 3 and 3^a it will be noted that the upper portion of the roller h^5

is solid, while the lower part thereof is recessed, so that said upper part will help the receptacle to dump evenly and easily at the required time.

At regularly-spaced points on the inner side of the ring E are pairs of vertical ears j , horizontally perforated to constitute bearings for the trunnions j' of a circular series of closely-related keepers J, said keepers being radially arranged, as indicated more clearly in Fig. 1. Each keeper comprises an outer sector-shaped body J', containing a plurality of radially-disposed and approximately rectangular openings, each of such plan dimension that it will substantially conform to the open top of one of the boxes. The body at its inner and outer sides, as well as ends, is constituted by a vertical flange j'' , the body being spanned by intermediate webs j''' , which form the distinct openings, the several flanges and webs being rounded at their tops, as indicated by j''' .

Inwardly extending from the top of the body is a shank J'' , which may be of the configuration disclosed in Figs. 1 and 4 and contracts toward the rear. At an intermediate point the shank has a transverse enlargement j^5 at its lower side, adapted to snugly fit between the ears j and perforated for the passage of a pin forming the laterally-projecting trunnions j' , while the inner end of the shank j^5 has an upper lug j^6 , in which is located a pin j^7 , headed to revolvably retain a roller j^8 .

It will be noted that the rollers h^5 of the boxes are in such circular arrangement that at one point of the rotation of the ring E they will be brought in contact with and roll upon the upper face of the trackway C'. Also the rollers j^8 of the keepers are so positioned that as the ring revolves they successively contact with one of the curved ends of the shoe G and are depressed to pass beneath the same, thereby tilting the keepers on their trunnions to raise the body portions thereof.

The boxes and keepers are so mounted in position that the body portion of each keeper normally rests by gravity upon the upper edges of the open tops of a plurality of the boxes, the openings in the keeper coinciding with the open tops of the boxes beneath.

In practice several attendants occupying suitable positions with respect to the machine are engaged in depositing in each box a previously-weighed quantity of the material to be packaged. The revolution of the box-carrying frame and continuous series of boxes thereon permits the material in distinct weighed quantities to be deposited in the successive boxes as they sweep past at a comparatively high rate of speed, dependent upon the character and condition of the material.

As each box is brought into proximity of the points when it is to discharge into the hopper of a packaging-machine, which hopper will be oppositely located with respect to the trackway C' and shoe G, the roller h^5 of

the box will pass upon said trackway and by reason of the frictional character of the latter be turned, thereby inverting its receptacle and delivering the contents thereof to the 5 hopper of the packaging-machine. The position of the shoe G is such, however, that immediately prior to the passing of the roller h⁵ onto the trackway, as described, the roller j⁸ of the keeper pertaining to the particular 10 box under consideration will move beneath and be depressed by the shoe G and effect the raising of the body portion of the keeper to permit the inversion of the box, as previously explained. As each keeper is shown as 15 acting with three of the boxes, the length of

the shoe G is such that the keeper is maintained raised until the third one of its boxes has discharged and is again brought to a position with its open end uppermost, at which 20 time the roller of its keeper will have passed beyond the shoe, permitting the keeper to resume its normal position upon the top of its group of boxes and said group and keeper to be moved around to a point where the boxes 25 can again have material deposited therein.

It will be appreciated that the general construction and arrangement of the boxes, keepers, and coacting parts are such that each 30 box will be positively operated to deposit its contents before the similar operation of the box succeeding, so that the successive quantities of material can deliver with precision, notwithstanding the considerable speed at which the box-carrier rotates. Furthermore, 35 the conditions aforesaid increase the capacity of the apparatus considered with a given number of boxes for the rapid delivery of the weighed quantities of the material to the packaging-machine.

40 The novel conveying and delivering means is not only extremely simple, embodying, as it does, comparatively few parts, but is not liable to irregularity of and interference with the proper working of the parts.

45 An important feature of my invention resides in the fact that the means for revolving the boxes or buckets at the predetermined periods and the device for releasing the keepers are located within the outer circumference of the rotary carrier, a highly compact arrangement thus resulting and the liability of interference with or derangement of such parts considerably reduced.

55 By employing a construction such as that described the material can be delivered by the means direct to the hopper K of the packaging-machine K', which on account of the overhanging of the rotating box-carrier can be compactly disposed beneath the same.

60 I do not wish to be understood as limiting myself to the particular construction and arrangement of parts shown and described, but reserve the right to such modifications as may be fairly considered within the scope of my 65 invention.

Having now described my invention, what I claim as new, and desire to secure by Letters Patent, is—

1. In conveying and delivering means, the combination with a circular horizontally-rotating carrier, of radially-disposed open-top buckets revolvably mounted in bearings in the carrier, a radial series of vertically-vibratable keepers, having their outer portions normally closely above the bucket-tops, and having 70 openings registering with those of the buckets, and provision for successively vibrating said keepers and revolving the buckets pertaining thereto, at one point of the carrier travel. 80

2. In conveying and delivering means, the combination with a circular horizontally-rotating carrier, of a series of radially-disposed open-top buckets revolvably mounted in bearings in the carrier, means tending to counter-balance said buckets, a series of radial vertically-vibratable keepers having openings registering with those of the buckets, said keepers normally retaining the buckets against rotation, and provision for successively vibrating said keepers and revolving the buckets pertaining thereto, at one point of the carrier travel. 85 90

3. In conveying and delivering means, the combination with a rotatable carrier, of a box 95 carried thereby, and a spring-supported trackway with which a portion of the box frictionally contacts to effect the discharge of the box at one point of its travel.

4. In conveying and delivering means, the combination with a movable carrier, of a box carried thereby, a spring-supported trackway with which a portion of the box contacts to effect the discharge of the box at one point of its travel, and provision for adjusting the degree of friction exerted by said trackway 100 against said portion. 105

5. In conveying and delivering means, the combination with a movable carrier, of a box 110 revolvably carried thereby, means for turning the box at one point of its travel, and provision for normally counterbalancing the box to maintain it in a non-discharging position.

6. In conveying and delivering means, the combination with a movable carrier, of a revolvable box carried thereby and having a roller, a portion of which is adapted to aid the box to dump evenly and easily when required, and provision with which said roller contacts and is turned to effect the turning of the box at 120 one point of its travel. 115

7. In conveying and delivering means, the combination with a movable carrier, of a revolvable box carried thereby, and provision for turning it at one point of its travel, a gravity-keeper normally retaining said box against discharge, and means for disengaging said keeper prior to and during the discharging operation. 125

8. In conveying and delivering means, the 130

combination with a horizontally-movable carrier, of a series of tilting boxes carried thereby, keepers each normally maintaining a plurality of boxes in an untilted position, provision for disengaging each of said keepers at one point of the carrier travel and successively tilting the groups of boxes pertaining thereto.

9. In conveying and delivering means, the combination with a horizontally-movable carrier, of a series of tilting boxes carried thereby, pivoted keepers each normally maintaining a plurality of boxes in an untilted position, a shoe for depressing the inner end of each of said keepers at one point of the carrier travel, and means for successively actuating the group of boxes pertaining to the tilted keeper.
10. In conveying and delivering means, the combination with a horizontally-movable carrier, of a series of tilting boxes carried thereby, pivoted keepers each normally maintaining a plurality of boxes in an untilted position, a shoe for depressing the inner end of each of said keepers at one point of the carrier travel, and means for successively actuating the group of boxes pertaining to the tilted keeper.

In testimony whereof I have signed my name to this specification in the presence of two subscribing witnesses.

EDWIN FIDELL.
